(57) **CLAIM**

The ornamental design for a front bumper for a vehicle, as shown and described.

DESCRIPTION

This application contains subject matter related to the following co-pending U.S. design patent applications:

Application Ser. No. 29/607,492, filed herewith and entitled "Vehicle, Toy, and/or Replicas Thereof"; and

Application Ser. No. 29/607,494, filed herewith and entitled "Front Bumper for a Vehicle".

FIG. 1 is a front view of a front bumper for a vehicle according to the design;

FIG. 2 is a top, front and right side perspective view thereof and;

FIG. 3 is a bottom, front and left side perspective view thereof.

FIG. 4 is a right side view thereof;

FIG. 5 is a left side view thereof;

FIG. 6 is a top view thereof;

FIG. 7 is a bottom view thereof; and,

FIG. 8 is a rear view thereof.
